(57) **CLAIM**

The ornamental design for a display screen with Bluetooth speaker, as shown and described.

DESCRIPTION

FIG. 1 is a front, right, top perspective view of a display screen with Bluetooth speaker showing our new design in which the display screen is folded;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is an exploded view thereof;

FIG. 9 is a front, right, top perspective view thereof in which the display screen is completely unfolded;

FIG. 10 is a front view thereof;

FIG. 11 is a rear view thereof;

FIG. 12 is a left side view thereof;

FIG. 13 is a right side view thereof;

FIG. 14 is a top plan view thereof;

FIG. 15 is a bottom plan view thereof; and,

FIG. 16 is an exploded view thereof.

The broken lines depict portions of the display screen with Bluetooth speaker that form no part of the claimed design.
